UNITED STATES PATENT OFFICE.

LEVI A. BEARDSLEY, OF SOUTH EDMESTON, NEW YORK.

BENCH-VISE.

Specification of Letters Patent No. 27,960, dated April 24, 1860.

To all whom it may concern:

Be it known that I, LEVI A. BEARDSLEY, of South Edmeston, in the county of Otsego and State of New York, have invented a new and Improved Bench-Vise; and I do hereby declare that the following is a full, clear, and exact description thereof, reference being had to the accompanying drawings, forming a part of this specification, in 10 which—

Figure 1 represents my improved vise; Fig. 2, the same invention applied to a wrench.

Similar letters of reference indicate 15 corresponding parts in the several figures.

To enable those skilled in the art to fully understand my invention I will proceed to describe its construction and operation.

The jaws, A A, are strongly pivoted to 20 two arms, B, which themselves are pivoted together at their lower ends at a; these four parts are made of suitable metal and work freely in their joints.

D is a right and left screw shaft tapped 25 through each jaw, A A, and having a suitable handle for turning the screw in opening or closing the jaws. In the middle of the screw, D, or at an intermediate point between the jaws, A A, is a small wheel, b, 30 which turns in a grooved projection, c, of a guide bar, E, and keeps this bar in place. This bar, in the vise of Fig. 1, is placed 35 under the screw, D, and passes through holes punched through the jaws at right angles to their inner faces. The wheel or annular

ring, b, with the projecting portion, c, of the guide bar, E, fits into the recess in the jaws, when the jaws are brought closely together the recesses are indicated by dotted lines in both figures.

J are arms riveted securely to one jaw, A, and serve to secure the vise to a bench or other convenient stand.

Now the object of the guide rod is to keep the jaws always parallel, and when they are 45 screwed up tightly to anything to prevent them from drawing on the screw threads and injuring the threads, the strain being equal consequently the jaws can be driven up with greater ease, and as they will 50 preserve their parallelism under any circumstances, unless the bar, E, bends or breaks, less power will be required to operate the screw to obtain a firm fixed bite.

By changing the position of the screw and 55 bar, and transposing them, a complete wrench will be obtained, operating upon the same principles as the vise.

Having thus described my invention what I claim, and desire to secure by Letters Patent, is—

The arrangement and combination of the pivoted jaws A, hinged arms B, guide bar E, recess c, right and left screw D, and ring b, as and for the purpose herein shown and 65 described.

LEVI A. BEARDSLEY.
